UNITED STATES PATENT OFFICE.

GUSTAV FISCHER, OF RIESA, GERMANY, ASSIGNOR OF FOUR-FIFTHS TO MAX RICHTER, OF DRESDEN, GERMANY, AND FRITZ WODA; HUGO MESTERN, AND PAUL PALLESTER, OF VIENNA, AUSTRIA-HUNGARY.

CARBURETER.

SPECIFICATION forming part of Letters Patent No. 679,019, dated July 23, 1901.

Application filed September 1, 1900. Serial No. 28,843. (No model.)

To all whom it may concern:

Be it known that I, GUSTAV FISCHER, mechanician, residing at Riesa, near Dresden, Kingdom of Saxony, Germany, have invented certain new and useful Improvements in Carbureted-Air Producers; and I do hereby declare that the following is a full, clear, and exact description of the same.

This invention has reference to an improved carbureted-air producer in which the production of carbureted air is automatically regulated by the demand of air-gas. The apparatus is constructed in such a manner that it is enabled to carburet air with all kinds of liquid hydrocarbons and to burn completely also heavy hydrocarbon, so that the produced air-gas is suitable for illumination, cooking, and the supplying of power.

In the accompanying drawings such a carbureted-air producer is represented in Figure 1 in combination with a hot-air motor. Fig. 2 is a vertical section through the apparatus; Fig. 3, a horizontal section of the carbureter on the lines I, II, III, and IV. Fig. 4 is a vertical sectional view, partly in elevation, of the pressure-reducing device. Fig. 5 is a horizontal sectional view through the upper portion of the vessel 18 of the pressure-reducing device, showing the weight which operates the valve 20 in dotted lines.

The apparatus consists, essentially, of the carbureter A, a blower B, a motor C to actuate the latter, an air-accumulator D, and one or more air-pressure-reducing devices and the necessary attachments.

There is nothing special in the construction of the motor C and the blower. In the drawings the hot-air motor and the blowing-engine are of well-known construction.

The carbureter A, Fig. 2, is of the following construction: A closed vessel 3 is provided with a filling device 1, an indicating-tube 2, and an air-feeding tube 4, terminating toward the bottom of the vessel 3 in a chamber 5. The bottom 6 of the chamber 5 is formed by the finely-perforated thin metal plate or a fine-wire sieve, so that the air passes into the liquid hydrocarbon in the form of many fine jets. On the air-feeding tube 4 is provided another chamber 7, in which

are arranged a number of horizontal vanes, forming a turbine wheel 8. The space over these vanes of the tube 4 is completely closed, and from this space lead one, two, or more radially-terminating tubes 9 to the chamber 7, 55 Fig. 3. On the lower part of the turbine-wheel axle 10 there are arranged one or more brushes 11, turning with the axle 10 and sliding over the perforated bottom 6 for the purpose of keeping the air-openings clean. In 60 order to enable the brushing device to adjust automatically, it is longitudinally movable on the axle 11. The air under pressure produced by the blower B entering through the tube 12, Fig. 1, and the cover 13 of the carbureter in 65 the upper part of the air-tube 4 is therefore dispersed and serves to actuate the cleaning device 11 of the air-openings, effecting simultaneously a regulating of the shocks. Before entering the carbureter the air is led into an 70 accumulator D, serving as an air-chamber. This air-accumulator consists of a closed vessel 14, the cover of which is provided with an outlet-valve 15 and provided internally with a pressure-reducing device, Figs. 4 75 and 5. The latter consists, essentially, of a vessel 18, closed by a diaphragm 17 of flexible metal or india-rubber, and is divided by a horizontal partition 16 into two compartments. The diaphragm is rigidly connected 80 to a vertically-movable rod 19, on which is secured a valve 20, closing a valve-seat in the partition 16. This valve is opened by the weight 21 of the diaphragm 17, so that the air entering below the partition passes 85 through the valve 20 below the diaphragm. When the pressure of the air sinks below a certain point, the diaphragm collapses slightly inward, opening the valve 20 between the two partitions and so permitting air 90 to flow into the reservoir. From the upper chamber of the pressure-reducing device the air passes through an opening 21^a in the accumulator 14 and fills the latter. The valve 15 is weighted by a weight-operated lever 22 95 and automatically opened by a suitable surcharge in the accumulator 14. Thus no more air enters in the carbureter as gas is consumed, while the superfluous uncarbureted air escapes through the outlet-valve 15.

In the accumulator is always a slight sur-charge. When the outlets are kept opened, the air will pass through the carbureting liquid and escape carbureted. When all the outlets are closed, the air cannot pass into the carbureter, but will open the outlet-valve 15 and escape through the same. Therefore no production of gas takes place. It is advantageous to lead the air through a second pressure-reducing device before it enters the carbureter, so that every shock is prevented. In the construction shown in the drawings there is shown a hot-air motor for the purpose of using part of the gas produced by the apparatus to actuate the motor, and while the air-current may serve for the cooling of the motor and also heating and drying of the air before it enters the carbureter, a part of the air heated by the motor may be led under the carbureter for the purpose of avoiding the formation of ice in consequence of cooling. The motor is of any well-known construction. On the lower cover the air-heating tube 24 and below the latter the burner 25 are arranged. The latter receives the gas through the gas-conduit 27. The motor-cylinder is provided with a jacket 28. The air-current produced by the blower B is led through the tube 31 in the chamber between the jacket and the cylinder for the purpose of heating and drying the air. From this chamber the hot air passes through the tube 32 in the accumulator. From the heating-tube 24 a conduit 28^a leads a part of the hot air below the carbureter for the purpose mentioned before. The blower B is actuated in well-known manner by means of the driving-rod 29 and the rocking axle 30, which is actuated by the fly-wheel of the motor. This apparatus is absolutely free from danger, and no surveying is necessary except the pressure to form the flame of the burner. The produced gas is suitable for direct and incandescent illumination, heating, and also for working in explosion-motors. Also an explosion-motor working with the carbureted air produced by the generator may be used instead of the hot-air motor, the other arrangement not being altered. The flame 25 can serve to light the gas in the motor-cylinder or to heat the glowing tube. The apparatus can also be actuated by hand.

Having thus described my invention, what I claim, and desire to secure by Letters Patent, is—

55

1. In a carbureting device the combination with a reservoir for hydrocarbon and a carbureted-air outlet therefor, of a chamber arranged within said reservoirs, an air-inlet for said chamber, a rotatable shaft within the chamber, a perforated bottom for the chamber, and brushes mounted upon the shaft and adapted to make contact with the perforated bottom.

2. In a carbureting device, the combination with a reservoir for hydrocarbon and a carbureted-air outlet therefor, of a chamber arranged within said reservoirs, an air-inlet for said chamber, a rotatable shaft within the chamber, a perforated bottom for the chamber, and brushes adjustably mounted upon the shaft and adapted to make contact with the perforated bottom.

70

3. In a carbureting device, the combination with a reservoir for hydrocarbon and a carbureted-air outlet therefor, of a chamber arranged within said reservoirs, an air-inlet for said chamber, a rotatable shaft within the chamber, a series of vanes secured to the upper part of the shaft, a perforated bottom for the chamber, and brushes mounted upon the lower part of the shaft and adapted to make contact with the perforated bottom.

75

4. In a carbureting device, the combination with a reservoir for hydrocarbon and a carbureted-air outlet therefor of an air-chamber within the reservoir having an air-inlet at the upper end, the said chamber having portions 7 and 5 intermediate its length, pipes 9 communicating with the upper part of the air-chamber and portion 7, and a perforated bottom for the part 5, a rotatable shaft in the air-chamber, vanes on said shaft within the part 7, and brushes upon the said shaft within the part 5 and adapted to make contact with the 95 perforated bottom.
